(57) **CLAIM**

The ornamental design for a tricycle as shown and described.

DESCRIPTION

FIG. 1 is a perspective view of a tricycle showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the tricycle where the tricycle is in a configuration of use;

FIG. 10 is an enlarged view of portion 10 shown in FIG. 1; and,

FIG. 11 is an enlarged view of portion 11 shown in FIG. 1. The dash-dash broken lines in the drawings depict portions of the tricycle that form no part of the claimed design.

The dot-dash broken line indicate the boundaries of the enlarged views and are used for annotative purposes only. They do not limit or define the scope of the claimed design.
